LISTING, ADDING MACHINE

Loring Pickering Crosman, Maplewood, N. J.,
 assignor to Gardner Company, Orange, N. J.,
 a corporation of Delaware

Application December 21, 1935, Serial No. 55,576

1 Claim. (Cl. 235—60)

The invention relates to listing adding machines, and more particularly to total and grand total printing mechanism therefor.

The invention consists in the novel construction and combination of parts, as set forth in the appended claim, and it is designed to provide for the accumulation of items; for the taking of totals and accumulation of the grand total, under control of the total key mechanism, all without manual readjustment of any control for selecting the particular accumulators to be operated, and for the taking for a grand total (after setting of a special control) upon operation of the total key.

15 In the accompanying drawings, illustrating the invention:

Fig. 1 is a left side elevation of an adding machine to which the invention has been applied, with the casing removed.

20 Fig. 2 is a fragmentary plan view of the keyboard.

Fig. 3 is a detail right side elevation of the accumulator control mechanism.

The invention is shown as applied to a Gardner listing adding machine containing a transfer total mechanism such as that disclosed in co-pending application, Serial No. 10,271, filed on March 9, 1935 by Loring P. Crosman, and entitled "Registers".

30 Machines of this type are provided with a plurality of accumulators 473, (Fig. 3) to which amounts set up on the keyboard are transferred by means of reciprocatory segmental racks 610. The gears of the desired accumulator are meshed 35 with the racks 610 during the counterclockwise movement of said racks to effect subtraction, and are meshed during the return or clockwise movement of the racks to effect addition.

The accumulators are engaged with the racks 40 by means of cams 453, 455, fast upon the respective accumulator shafts, in cooperation with cams 452, mounted upon the frame of the machine, engagement of a cam 452 with a cam 453 serving to move the shaft 403 of an accumulator 473 45 along suitable guide slots of the framing against the tension of suitable springs, to effect the meshing. The cams 453, 455 are adjusted through the shafts 403 to determine whether a given accumulator shall be operative or shall remain idle. 50 Cams 452 are formed upon rocking plates 419, 421 having a pin and slot connection with each other at 71, the plate 419 being connected by means of a link 321 and arm 322 with a rocker 325. The rocker 325 is controlled by rock shaft 301, which 55 is moved in time with the racks 610, and serves

to determine whether the active accumulator shall be operated additively or subtractively. This control is effected in a known manner (application Serial No. 10,271; patent to Mixer, No. 1,927,-878, of September 26, 1933, etc.) by means of cam arms 316 and 320 fast to the shaft 301 and forward and rear cam followers pivotally connected to the rocker 325.

Total printing

10

Totals are printed, as is usual in machines of this type by engaging one of the accumulators with the racks 610 and allowing these racks to move subtractively until the accumulator is stopped at zero, thus entering the total on the 15 racks and thereby on the type bars of the machine. The printing hammers are then released, the accumulators disengaged from the racks, and the parts restored to normal position.

In the combination employed in the present invention, a total cleared from the upper accumulator 473 is transferred to the lower accumulator, this being effected in the preferred construction by means described in co-pending application, Serial No. 10,271.

20 A total key 278 is provided with a shoulder engaging a pin 352 fixed in a plate 326, pivoted concentrically with the rocker 325, depression of the total key moving the plate 326 clockwise as viewed in Fig. 3, to disable the rear cam follower, to withdraw a shoulder of the plate from the rear face of a pin in the upper end of the forward cam follower, and to bring a second shoulder of said plate in front of the pin. In this position of the parts the cam arm 320 will rock the forward cam 35 follower idly about its pivot during the subtractive stroke of the racks 610, leaving the cams 452 in the position shown in Fig. 3, wherein it will be noted that the upper accumulator 473 is held up against the racks 610 while the lower accumulator 40 remains in its forward or idle position. At the end of the forward stroke of the racks, the forward cam follower will escape from the rear end of cam 320, so that upon the return stroke of the parts this cam follower, held by the shoulder 45 of the plate 326, will move the rocker 325 clockwise, and thereby move the plates 419, 421 so that the upper cam 452 is moved downwardly out of contact with the cam 453, allowing the upper accumulator to move out of meshing engagement with the racks during the additive stroke.

The lower accumulator 473 is thrown into mesh with the racks 610 during the additive stroke thereof by the following means:

55

Upon depression of the total key 278, a pin 73, fixed in the key lever will engage a pawl 72 mounted upon an arm 70, fixed upon a shaft 62. A second arm, 71 is also fast upon shaft 62, this arm being connected, by a link 74, with a latch 75. Latch 75 is pivoted upon a plate 76 which is in turn pivoted concentrically with the plate 418 and is provided with a cam face 78. Depression of key 278 will therefore rock shaft 62 in a clockwise direction as viewed in Fig. 3, and arm 71 will act to engage the latch 75 with the pin 77 of the plate 418, holding the plate 418 and the plate 76 in fixed relation, for operation in unison. Thus, at the beginning of the additive stroke of the racks 610, the upward rocking movement of plate 418, effected by the readjustment of rocker 325, will bring the cam face 78 in contact with a collar 80 of the lower shaft 403, and will thereby force the lower accumulator into mesh with the racks 610, whereby the total, which has been transferred to the racks from the upper accumulator will be added into the lower accumulator during the return stroke of said racks.

25 *Grand total printing*

At the end of a series of operations, it will be desired to print the grand total which has been accumulated from time to time on the lower accumulator, for which purpose, according to the present invention, the upper accumulator is moved to inactive position, the lower accumulator is thrown into mesh with the racks 610 at the beginning of the operation, and the transfer total mechanism is disabled, the total then being printed and the lower accumulator cleared in the usual manner.

It is designed that a grand total shall be taken by means of the total key 278, in cooperation with a grand total control lever 1 (Figs. 1 and 2). Preferably lever 1 is a spring retracted member, and must be held in active position by the operator until the total key is depressed, this method of operation serving to prevent inadvertent clearing of the grand total on the lower accumulator. Lever 1 is fulcrumed on the frame of the machine at 2, and is provided with a retraction spring 81. In moving from neutral to active position, a pin 82 in grand total lever 1 will engage and displace a pin 83, fixed in a yieldable slide plate 84. Slide plate 84 extends across the front of the machine as seen in Fig. 2, and is provided at its right hand end with a lug 85, adapted upon displacement of plate 84 by lever 1 to move beneath a shoulder 86 of the total key 278, thus serving to lock the total key in inoperative position while the lever 1 remains in partially adjusted position. Grand total lever 1 having been fully moved to active position, the depression of total key 278 will bring the shoulder 86 into the path of movement of lug 85 of plate 84, and the grand total lever will remain locked in active position so long as the total key remains depressed.

Movement of lever 1 to active position will effect the proper setting of the upper and lower accumulators, by means of a roller 4, fixed in the lower end of lever 1, and engaging a cam wall 8 of a segment 8, pivoted at 9 to the framing of the machine. Segment 8 has rack teeth engaging pinions 474, fixed upon shafts which are provided with universal joint connections with the

5 accumulator shafts 403. Therefore, rearward movement of lever 1, into its active position, will raise the segment 8 and effect clockwise movement of the pinions 474, as viewed in Fig. 1, this movement corresponding to a third of a rotation 10 in a counterclockwise direction of the cams 453, 455, as viewed in Fig. 3. As will be observed in Fig. 3, this rotation of cams 453, 455 will allow the upper accumulator to drop out of mesh with the racks 610 and, through engagement with the 15 cams 455 and 452, will force the lower accumulator into mesh with said racks.

Rearward movement of lever 1 will disable the transfer total mechanism by means of a pin 87, fixed in the lever 1 and normally forming a stop 15 for a spring arm 88, fast upon the shaft 62. Forward movement of lever 1 will move pin 87 away from the shaft 62, the spring of arm 88 thereupon rocking shaft 62 in a clockwise direction as viewed in Fig. 1, or counterclockwise as viewed in Fig. 3, 20 thus moving the pawl 72 from position under the pin 73 of the total key.

Therefore, in the grand total operation, the upper accumulator 473 will remain idle, while the lower accumulator will be held in operative 25 position until the end of the subtractive stroke of the machine, and will then, owing to the movement of rocker 325, withdrawing cam 452 from engagement with cam 455, be allowed to move into idle position. The operation of the known 30 total printing device has thus taken a total from the lower accumulator, instead of taking it from the upper accumulator as in transfer total operations.

In an illustrative operation of the machine, 35 items may be accumulated in the upper accumulator only, from which totals are transferred from time to time to the lower accumulator, in which such totals are accumulated as a grand 40 total. Obviously, the parts which control the 45 operation of the particular accumulators may be set for other than the above described grand total work, when so desired. For instance, an old balance may be added directly into the grand total accumulator, before the series of operations 50 above described is started.

Grand totals are taken, usually, at infrequent intervals, ordinarily and the present invention provides a machine wherein it will not be necessary to manually adjust the accumulators into 55 or out of active position except when such grand total is taken, and it also provides that both transfer totals and grand totals shall be taken upon operation of the same total key, and total key mechanism.

55 I claim:

In a listing adding machine having an item accumulator and a grand total accumulator, the combination with a lever, means selectively settable by said lever to render either selected accumulator active, and total printing mechanism including a total key and means operable by said key to take a total from the accumulator which is in active condition, of transfer total means normally operable by the total key to set the 65 grand total accumulator to accumulate a total taken from the item accumulator, and means operable by the lever, in its grand total accumulator selecting position, to disable said transfer total means.

70 LORING PICKERING CROSMAN.
